UNITED STATES PATENT OFFICE.

HARLAN E. HUNTSBERRY, OF CLEVELAND, OHIO.

CLAM-SHELL BUCKET.

933,455.

Specification of Letters Patent. Patented Sept. 7, 1909.

Application filed March 22, 1909. Serial No. 434,884.

To all whom it may concern:

Be it known that I, HARLAN E. HUNTSBERRY, a citizen of the United States of America, residing at Cleveland, in the county of Cuyahoga and State of Ohio, have invented certain new and useful Improvements in Clam-Shell Buckets; and I hereby declare the following to be a full, clear, and exact description of the invention, such as will enable others skilled in the art to which it pertains to make and use the same.

This invention relates to new and useful improvements in clam-shell buckets and operating mechanism therefor especially adapted for handling iron-ore and similar material.

One object of this invention is to provide a bucket of this character which will be simple in construction, durable and which will have a very large reach or stretch in comparison to its height when open.

A further object of my invention is to provide a bucket which while having a good digging action will also be able to dispose of its load very quickly.

My invention therefore consists in the new and improved means for operatively connecting the arms which suspend the front and rear ends of the scoops and applying power thereto.

The bucket comprises two scoops or trays which when brought together form a single receptacle for the reception of the material which is to be handled. Each end of each scoop is suspended by a pair of arms and for the sake of convenience of description the arms secured near the cutting edge of the scoops or trays will be termed the front arms and the arms secured near the opposite end of the scoops will be termed the rear arms. The rear arms of each scoop are formed considerably longer than the front arms and at their upper ends are preferably hung from the same supporting shaft. The upper ends of the front arms of each scoop are connected to the rear arms by means of a pair of links or lever arms which are operatively connected at their upper ends to the upper ends of the front arms and are fulcrumed at a point intermediate of their ends on the rear arms at a point intermediate of the ends of said rear arms. The lower ends of the two pairs of lever arms are operatively connected together and are also operatively connected to the upper ends of the rear arms by means of a cable hereinafter termed the

opening cable, and the lower ends of the two pairs of front arms are operatively connected by means of a closing cable.

In the accompanying drawing Figure 1 is a side elevation of a bucket embodying my invention in its closed position. Fig. 2 is an end elevation of the same. Fig. 3 is a side elevation showing the bucket open.

Again referring to the drawings 1 and 2 represent the trays or scoops which together form the receptacle for holding the material which is being excavated. From a shaft 3 are suspended two pairs of straight arms, one pair of which, 4, extends to the rear end of the scoop 1 and the other pair, 5, extends to the rear end of the scoop 2 and pivotally are secured thereto by shafts 6 and 7 respectively. To the sides of the respective scoops 1 and 2, at the front ends thereof, are pivotally secured the lower ends of a pair of front arms, indicated by 9 and 10 respectively, by means of bolts 11 and 12 respectively. These arms are preferably offset at their lower ends so that sheaves mounted on the outside of said arms will not project beyond the sides of the said scoops. A shaft 13 extends between the pair of rear arms 4 and a shaft 14 extends between the pair of rear arms 5, and on each shaft is fulcrumed a pair of links or lever arms, indicated as 15 and 16. These lever arms are fulcrumed at a point between their centers and their upper ends so that the longer ends of said lever arms extend downwardly when the bucket is in its closed position. The upper ends of the pair of lever arms 15 are pivotally connected to the upper end of the pair of front arms 9 by means of bolts 17 and the upper ends of the pair of lever arms 16 are pivotally connected to the upper end of the pair of front arms 10 by bolts 18. The lower ends of the said pairs of lever arms 15 and 16 are operatively connected together by means of a shaft 19. On the shaft 19 are mounted a pair of sheaves 20. A shaft 21 extends between the lower ends of the pair of front arms 9 and projects beyond each arm, and on the projecting portion of said shaft, at each end, is mounted a sheave 22. A shaft 23 extends between the lower ends of the front pair of arms 10 and projects beyond each arm, and on the projecting portion of said shaft, at each end, is mounted a sheave 24. The sheaves 22 and 24 are preferably provided with guard casings 25 and 26 respectively which prevent the cables from slipping off of the said sheaves and

also protect the sheaves from the material which is being excavated. At each end of the shaft 3 outside of the arms is arranged a swinging pulley or guide-sheave 27, and on said shaft inside of the arms are hung a pair of swinging pulleys or guide-sheaves 28. A pair of opening cables 30 and a pair of closing cables 31 are provided, one opening cable and one closing cable being operatively connected at each side of the bucket so that the bucket will hang evenly. Each opening cable 30 is secured to the main shaft 3, preferably by means of the end thereof being spliced to the frame of a sheave 28 and is then carried down and around a sheave 20 on the shaft 19 and then up through a guide sheave 28 on the shaft 3. One end of each closing cable is secured to the guard casing 26 of a sheave 24 and is then carried around a sheave 22 and then around said sheave 24 and up through the guide sheave 27.

The operation of the bucket is as follows:—A pull on the opening cables will draw the lower ends of the lever arms and the upper ends of the rear arms toward each other causing the lower ends of the rear arms to swing out until the said arms assume a very wide angle, also the upper ends of the lever arms will at the same time swing out and downwardly shoving down the front arms on the respective scoops thereby tilting the scoops until they stand approximately at a right angle to the position they occupied in the closed position of the bucket. When it is desired to close the bucket it is only necessary to slacken the opening cables and then the pull on the closing cables will draw the front ends of the scoops together through the material which is to be excavated, and while the front ends of the scoops are being pulled together the action of the lever arms will draw up the front ends of the scoops thereby quickly changing the position of the scoops from vertical to horizontal so that the material will readily enter the scoops thereby avoiding all unnecessary waste of power in closing the bucket.

What I claim is,—

1. In a clam-shell bucket, the combination of a pair of scoops, swinging arms pivotally secured to the rear ends of each scoop, arms secured to the front end of each scoop, lever arms fulcrumed on each pair of rear arms and having their upper ends pivotally secured to the upper ends of the front arms, and having their lower ends operatively connected together, means for causing the upper ends of the rear arms and the lower ends of the lever arms to approach each other and means for causing the front ends of the scoops to approach each other, for the purpose set forth.

2. In a clam shell bucket, the combination of a pair of scoops, arms pivotally suspended at their upper ends and pivotally secured to

the rear end of said scoops at their lower ends, shorter arms pivotally secured at their lower ends to the front ends of said scoops, lever arms fulcrumed between the rear arms at a point between the centers of said lever arms and their upper ends, means for pivotally connecting the front arms to the upper ends of said lever arms, means operatively connecting the lower ends of said lever arms, means for causing the lower ends of said lever arms and the upper ends of said rear arms to approach each other, and means for causing the front ends of said scoops to approach each other.

3. In a clam shell bucket, the combination of a pair of scoops, a pair of arms pivotally secured at their lower ends to the rear ends of each scoop, means for pivotally suspending the upper ends of said arms, a pair of arms pivotally secured to the front end of each scoop, said front arms being shorter than said rear arms, a pair of lever arms fulcrumed between each pair of rear arms at a point intermediate of their ends, means for pivotally securing the upper ends of each pair of front arms to the upper ends of the corresponding pair of lever arms, a shaft connecting the lower ends of said pair of lever arms, a sheave mounted on said shaft and a rope having one end operatively secured to the upper ends of the rear arms and passing around said sheave on said lever arms.

4. In a clam-shell bucket, the combination of a pair of scoops, arms pivotally secured to the rear ends of said scoops at their lower ends, arms pivotally secured to the front ends of said scoops, lever arms fulcrumed on said rear arms, means for pivotally connecting said lever arms at a point above their point of fulcrum to the upper ends of said front arms, and means for causing the opposite ends of said lever arms and the upper ends of said rear arms to approach each other.

5. In a clam shell bucket, the combination of a pair of scoops, a shaft, arms hung from said shaft and pivotally secured to the rear end of said scoops, lever arms fulcrumed on said first-mentioned arms, arms pivotally hung from the upper ends of said lever arms and pivotally secured at their lower ends to the front ends of said scoops, a shaft connecting the lower ends of said lever arms, sheaves mounted on said shaft, sheaves mounted on the lower ends of the front arms, opening cables operatively connected to the upper end of the rear arms and passing around the sheaves on said shaft connecting the lever arms, closing cables operatively connected to the front end of one scoop and passing around the sheaves on the lower ends of the front arms, for the purpose set forth.

6. In a clam shell bucket, the combination

of a pair of scoops, a shaft, two pairs of arms suspended from said shaft, each pair being secured at their lower ends to the rear end of one of said scoops, lever arms fulcrumed 5 between each pair of said rear arms so that a portion of said lever arms extends upwardly beyond the point of fulcrum, a pair of arms pivotally secured at their upper ends to each pair of lever arms and at their lower ends to the front ends of said scoops, means 10 for causing the rear arm supporting shaft

and the lower ends of said lever arms to approach each other, and means for causing the front arms to approach each other, for the purpose set forth.

15

In testimony whereof, I sign the foregoing specification, in the presence of two witnesses.

HARLAN E. HUNTSBERY.
